UNITED STATES PATENT OFFICE.

ARTHUR G. HARRIS, OF PALISADES, COLORADO.

FLY-PAPER GUARD.

1,165,251.

Specification of Letters Patent. Patented Dec. 21, 1915.

Application filed April 27, 1912. Serial No. 693,567.

To all whom it may concern:

Be it known that I, ARTHUR G. HARRIS, a citizen of the United States of America, residing at Palisades, in the county of Mesa and State of Colorado, have invented new and useful Improvements in Fly-Paper Guards, of which the following is a specification.

This invention relates to improvements 10 in protectors or guards and has particular application to a device of this character for holding fly paper or substances of a like nature so that such substance may be held against accidental movement and held in a 15 substantially closed condition so that contact with the paper is avoided.

In carrying out my present invention, it is my purpose to provide a protector or guard for fly paper and the like which shall act to 20 keep the paper or other substance in its initial position and which shall substantially inclose the paper to prevent contact with the same and at the same time permit the ingress of flies and similar insects to the 25 paper so as to trap or exterminate such insects.

Furthermore, I aim to provide a device of the above stated class which shall include a tray designed to receive a sheet of fly paper 30 or the like, and a guard detachably associated with the tray and capable of being securely fastened thereto so as to present a neat compact and efficient protector.

With the above and other objects in view, 35 the invention consists in the construction, combination and arrangement of parts hereinafter set forth in and falling within the scope of the appended claim.

In the drawing forming a part of this 40 specification: Figure 1 is a top plan view of a protector constructed in accordance with the present invention. Fig. 2 is a transverse sectional view of the same. Fig. 3 is a detail perspective view of the tray, 45 and Fig. 4 is a similar view of the guard.

Similar reference characters designate like parts throughout the several views.

Referring to the accompanying drawing in detail, the improved protector includes a 50 tray 1 constructed preferably of metal although any other suitable material may be utilized and of a size sufficient to receive a sheet of fly paper or other material of a like nature. In the present instance, the 55 longitudinal side edges of the tray 1 are

bent or turned upon themselves to provide flanges 2 which form, with the adjacent portions of the main body of the tray, grooves 3. One end of this tray is open, while the opposite end is closed through the medium of a bent up portion 4 arranged transversely of the flanges 2 and co-operating with the main body portion of the tray to provide a groove 5 contiguous the grooves 3 and transversely thereof.

Detachably associated with the tray 1 is a guard 6 composed, in this instance, of a frame consisting of longitudinal metallic side bars 7 and transverse metallic end bars 8, and a foraminous body 9 composed preferably of coarse wire screening and secured to the side and end bars of the frame in such a way that the main body of the screen will be held spaced above said side-bars 7, and the arrangement will also be such that the 75 guard will be closed on all sides, thereby preventing any object coming in contact with the fly-paper. This guard 6, after the fly paper has been deposited on the tray 1, is adapted to be slid longitudinally of the 80 said tray and within the grooves 3 thereof so as to cover the fly paper and render the same proof against contact with foreign objects, the foraminous body of the protector being of a construction to permit the ingress 85 of flies and other insects to the paper.

The open end of the tray 1, in this embodiment of the invention, is stamped to provide a spring catch 10 designed to engage the respective end bar 8 to prevent displacement of the parts when the latter have been 90 assembled in protector formation.

While I have shown and described one embodiment of my invention by way of illustration, it is to be understood that I do not 95 limit myself to all of the details or construction hereinbefore set forth, as variation and modification may be made within the scope of the claim without departing from the spirit or sacrificing any advantages of the 100 invention.

I claim:

The combination with a rectangular shaped tray adapted to receive a sheet of fly paper and having its longitudinal sides 105 and one end bent inwardly at their tops in spaced relation from the bottom of the tray to provide grooves and open at the opposite end, with a catch member stamped therein of a foraminous guard having a flat top 110

and downwardly and outwardly inclined sides, adapted to slide longitudinally within said grooves and be raised or lowered therein, whereby to prevent buckling of the paper
5 upon insertion of the guard and to completely inclose the fly paper and, be held secured in the tray by the said catch member.

In testimony whereof I affix my signature in presence of two witnesses.

ARTHUR G. HARRIS.
